UNITED STATES PATENT OFFICE.

GEORGE WHARTON, OF JERSEYVILLE, ILLINOIS.

IMPROVEMENT IN PLOWS.

Specification forming part of Letters Patent No. 105,531, dated July 19, 1870.

To all whom it may concern:

Be it known that I, GEORGE WHARTON, of Jerseyville, in the county of Jersey and State of Illinois, have invented a new and useful Improvement in Plows; and I do hereby declare that the following is a full and exact description of the same, reference being had to the accompanying drawings, and to the letters of reference marked thereon.

This invention has for its object the production of a plow which shall be capable of adjustment at the foot of the standard; and it consists in the combination of a curving beam, standard, and mold-board, as will be fully described hereinafter.

In the drawings, Figure 1 represents a side elevation; Fig. 2, a plan view of my improved plow, and Fig. 3 a partial view of the stand and beam.

To enable others skilled in the art to make and use my invention, I will now proceed to describe fully its construction and operation.

A represents the plow-beam, which is preferably constructed of iron and of the swan-neck form. B represents the standard; C, the share; D, the landside, and E E the handles.

The beam and handles are pivoted to the top of the standard by a bolt, as shown in Fig. 1. The lower and rear end of the beam is secured to the lower end of the standard by means of a bolt passing through any one of the orifices a a. The vertical adjustment of the front end of the beam is accomplished, when desired, by removing the bolt and moving the

beam until the desired hole is brought in line with the orifice of the standard, when it may be again secured as before. It will be observed, also, that the front ends of the handles are provided with orifices, by means of which their height may be adjusted at will in a similar manner. Lateral adjustment of the draft upon the plow-beam is permitted by means of the orifices a' a' in the front end of the plow-beam.

The plow herein described has many advantages. By applying the draft to the lower part of the plow it is enabled to run much more steadily than when otherwise applied. The adjustment is readily made, when desired, of either handles or beam. The clearance-space between the beam and the mold-board is very large, which fact especially fits the plow for use in stubble or trashy land.

Having thus fully described my invention, what I claim as new, and desire to secure by Letters Patent, is—

The plow described, provided with the curving beam A, standard B, and plow C, when the plow is rigidly attached to the standard and the beam is adjusted substantially as described, for the purpose set forth.

This specification signed and witnessed this 17th day of December, 1869.

GEO. WHARTON.
